UNITED STATES PATENT OFFICE

167,005

COMBINED BELL AND BOTTLE CAP REMOVER

Sajjan Singh Sarna, New York, N. Y.

Application January 25, 1952, Serial No. 18,216

Term of patent 3½ years

(Cl. D44—29)

To all whom it may concern:

Be it known that I, Sajjan Singh Sarna, a citizen of the United States of America, residing at New York, State of New York, have invented a new, original, and ornamental Design for a Combined Bell and Bottle Cap Remover, of which the following is a specification, reference being had to the accompanying drawing, forming a part hereof.

Fig. 1 is a front elevational view of a combined bell and bottle cap remover showing my new design;

Fig. 2 is a side elevational view thereof;

Fig. 3 is a rear elevational view thereof; and

Fig. 4 is a top plan view thereof.

I claim:

The ornamental design for a combined bell and bottle cap remover, as shown.

SAJJAN SINGH SARNA.
